UNITED STATES PATENT OFFICE.

HENRY C. VOGEL, OF PHILADELPHIA, PENNSYLVANIA.

BOTTLE-WASHER.

No. 855,912.

Specification of Letters Patent.

Patented June 4, 1907.

Application filed September 29, 1906. Serial No. 336,712.

To all whom it may concern:

Be it known that I, HENRY C. VOGEL, a citizen of the United States, residing in the city and county of Philadelphia, State of Pennsylvania, have invented a new and useful Bottle-Washer, of which the following is a specification.

My invention relates to bottle cleaning or washing machines and consists of means for adjusting the same for various sized bottles.

It further consists of novel details of construction, all as will be hereinafter fully set forth.

Figure 1 represents a side elevation of an attachment for bottle washing machines whereby various sized bottles may be accommodated. Fig. 2 represents a vertical sectional view thereof. Fig. 3 represents a side elevation of the device taken from the left of Fig. 1. Fig. 4 represents a sectional view on line $x-x$, Fig. 3.

Similar numerals of reference indicate corresponding parts in the figures.

Referring to the drawings:—My invention is designed for quickly and expeditiously adjusting the bottle holding means of a washing machine and is more particularly adapted for use with those machines which are known as the "Eick" as shown in Letters Patent No. 463,360, dated November 17, 1891, but it will be evident that the same can be applied to other types of machines and that while I have shown mechanism for carrying out my invention, other instrumentalities may be employed for accomplishing the same result. In the "Eick" machine, as now on the market, it is necessary that hooks be used for holding the upper plate of the bottle holders in elevated position while the parts are adjusted to accommodate the different sized bottles. This operation takes some time and is not always accurate.

In the present invention I am enabled, by simply turning the hand wheels to adjust the upper plate, so that between it and the lower plate the various sized bottles may be acted upon.

In the drawings I have omitted, for the sake of clearness and because they form no part of my invention, the greater portion of the bottle washing machine and have shown but one standard used in said machines, although it will be understood that in other machines there are two standards and the same mechanism, as I have shown and described, for one standard is placed upon the other standard.

1 designates an upright or standard on one side of the machine to which is adjustably secured the lower plate 2, which supports the bottles and in which are a plurality of openings adapted to receive the mouth of the bottle and through which openings the pipes, which lead to or are connected with a suitable source of supply, discharge the water or other cleansing fluid into the bottle.

3 designates one of the collars which support the plate 2 and which are mounted on the standards 1. Passing through said collar is a rack 4 which extends upwardly adjacent the standard 1 and is provided with a scale 5, indicating at what point it is necessary that the parts be situated in order to accommodate the various sized bottles.

6 designates a second collar movably mounted on the standard 1 and in which is journaled a pinion 7, which has connected therewith, a rod 8 having a hand wheel 9 thereon, said pinion 7 meshing with the teeth of the rack 4.

10 designates a movable sleeve slideable on the standard 1 and to which is connected one end of a spring 11, the opposite end of which is connected with the collar 6, in order that said sleeve and collar are normally held in contact.

12 designates the top plate of the bottle holding means which is carried by the sleeve 10 and upon the upper surface of which bears a cam 13 which is connected by means of a collar 14 with a rod 15, the ends of which are situated in suitable recesses 16 in the collars 6 at each side of the machine.

17 designates the operating lever connected with the rod 15.

The operation of the device will be readily seen: When it is desired to wash bottles, say of six inches, the collar 6 is adjusted by rotating the hand wheels 9 until the said collar is situated at a suitable point upon the scale 5, at which time the collar can be set at this point by the set screw 18. The bottles 19, which may be carried in a suitable rack or other means, are placed between the bottom plate 2 and the upper plate 12, the distance between these plates being slightly greater than the size of the bottle. As soon as they are in position, the operating handle 17 is operated in the direction indicated by the arrow, Fig. 3, when the bottles will be clamped between the two plates and the washing of the bottles occur. By releasing the handle 17 the bottles can be removed from

between the plates, it being understood that the cam 13 is actuated when the lever or handle 17 is operated in order to press down the upper plate 12, which thus overcomes the tension of the spring 11, causing, by a slight movement, the upper plate to engage the bottle. If a different sized bottle, for example, a seven inch bottle, is to be washed by turning the hand wheels 9 until the collar 6 is at the proper place on the scale, the space between the upper plate 12 and the lower plate 2 will be suitable for this size bottle when the handle 17 is again operated for clamping the bottles.

15 It will be understood by rotating the hand wheels 9 on each side of the machine that the pinions 7 are rotated and travel on the racks 4 carrying with them the collars 6 and sleeves 10 so that the upper plate 12 is caused to approach or move away from the lower plate 2.

Having thus described my invention, what I claim as new and desire to secure by Letters Patent, is:—

1. In a device of the character described, 25 a standard, a collar movable thereon, one portion of a bottle-holding means in suitable connection with said collar, a rack, the remaining portion of the bottle-clamping means connected with said rack, and means 30 carried by said collar engaging with said rack whereby said collar can be adjusted on said standard.

2. In a device of the character described, 35 a standard, a collar movable thereon, one portion of a bottle holding means in suitable connection with said collar, a rack, the remaining portion of the bottle-clamping means connected with said rack, a pinion carried by said collar engaging with said rack whereby 40 said collar can be adjusted on said standard and means carried by said collar for engaging the portion of the bottle clamping means carried by said collar.

3. In a device of the character described, 45 a standard, a collar movable on said standard, a rack, means carried thereby adjustable on said standard and serving as the bottom portion of the clamping means, a pinion carried

by said collar meshing with said rack, whereby said collar can be adjusted, a sleeve, a 50 plate carried by said sleeve serving as one portion of a bottle clamping means and a yielding device connecting said collar and sleeve.

4. In a device of the character described, 55 a standard, a collar movable on said standard, a rack, means carried thereby adjustable on said standard and serving as the bottom of the clamping means, a pinion carried by said collar meshing with said rack, whereby said 60 collar can be adjusted, a sleeve yieldingly connected with said collar, a plate carried by said sleeve serving as one portion of a bottle clamping means, and means connected with the collar and contacting with said plate for 65 moving the same.

5. In a device of the character described, 70 a standard, a collar movable on said standard, a rack, means carried thereby adjustable on said standard and serving as the bottom portion of the clamping means, a pinion carried by said collar meshing with said rack, whereby said collar can be adjusted, a sleeve yieldingly connected with said collar, a plate carried by said sleeve serving as one portion of a 75 bottle clamping means, and a cam connected with the collar and contacting with said plate for moving the same.

6. In a device of the character described, 80 a standard, a collar movable on said standard, a rack, means carried thereby adjustable on said standard and serving as the bottom portion of the clamping means, a pinion carried by said collar meshing with said rack, whereby said collar can be adjusted, a sleeve yieldingly connected with said collar, a plate carried by said sleeve serving as one portion of a 85 bottle clamping means, a cam connected with the collar and contacting with said plate for moving the same and a lever for operating 90 said cam.

HENRY C. VOGEL.
